SELECTOR

Helge Edvard Lindström, Stockholm, Sweden, assignee to Telefonaktiebolaget L. M. Ericsson, Stockholm, Sweden, a company of Sweden

Application October 19, 1938, Serial No. 235,855
In Sweden December 21, 1937

6 Claims. (Cl. 179—27.52)

The present invention relates to selectors of the type in which a multiple common to a plurality of selecting mechanisms is provided, and in which said multiple consists of bare wires or rods which extend substantially at right angles 5 to the direction of movement of the wipers during the selecting operation.

Known selectors of this type have the inconvenience that the bank of contacts and the selecting mechanism have to be separately attached to the selector frame by means of a plurality of members, resulting in that the mutual 10 positions of the selecting mechanism and the bank of contacts becomes dependent on the measure of accuracy with which the individual supporting or auxiliary members can be manufactured. In such selectors a fine adjustment of the position of the bank of contacts with respect to the selecting mechanism is required in connection with the assembling of the selectors. 15

The present invention has for its object to eliminate said inconvenience and to simplify the construction and manufacture of the selector. It consists substantially in the provision, between the selector mechanism and the bank of 20 contacts, of a plate which is perpendicular to the direction of movement of the wipers during the selecting operation, said plate serving on the one hand as an abutment for supporting insulating members which hold together different 25 bundles of wires or rods forming different groups of contacts, and serving on the other hand as an abutment for projections or lips provided on the base plate or the like for the selecting mechanism. According to the invention the abutting surface is formed as a supporting wall for the bank of contacts, said supporting wall also constituting a wall in a compartment for housing 30 one or more selecting mechanisms.

The invention will now be described more in detail having reference to the drawing attached to this specification and forming part thereof, which drawing shows a general perspective view 35 of a selector according to the invention.

Further to the left on the drawing there is shown the construction of the wire or rod 40 bundles forming the different groups of contacts of the selector multiple. The wire bundle TR consists of eleven pairs of wires held together by means of insulating pieces J which can be attached to the wires by a pressing operation. The insulating pieces are provided at one end with a projection P and at the other end with a nose N, the provision of said nose rendering it possible, 45 as will be clear from the following, to use the

insulating pieces as supporting members for the wire bundles so as to ensure their correct positions with respect to the other parts of the selector.

In the embodiment of the invention shown, the two main parts of the selector, or the multiple field and the selecting mechanism, are arranged at opposite sides of a plate A formed as a supporting wall for the multiple field, said supporting wall also constituting one of the walls of a compartment F for the selecting mechanism. As will be clear from the drawing the supporting wall A is provided for said purpose with recesses or guide apertures U into which the insulating pieces J, which hold together the wire bundles TR, may be inserted with their noses N, said noses after insertion engaging with the lower edges of the recesses in the manner of hooks.

Supported on the abutting surface of the wall are also brackets K, which form supports for a ledge T extending between them, said ledge being provided with recesses G corresponding to the projections P on the insulating pieces J of the multiple field. The ledge is also provided with a rubber packing M or the like and with screw fastenings V arranged in slots R at the ends of the ledge in such a manner as to enable the insulating pieces, and thus also the wire bundles, to be held between the ledge T and the abutting surface of the plate A by fitting the projections P into the recesses G. As a result of the pressing of the insulating pieces from a suitable substance, for example "Bakelite," shoulder surfaces S are also provided thereon, the distances of said shoulder surfaces from the nearest multiple wire being for different wire bundles constant within very narrow limits. The elastic packing arranged on the ledge T provides a completely tight contact between the shoulder S and the abutting surface, said surface being preferably also produced through a pressing or pressure casting operation.

The insulating pieces are preferably arranged on the wire bundles with a pitch corresponding to the vertical dimension of the space occupied by each selecting mechanism, brackets being also provided on the supporting wall A at mutual vertical distances corresponding to the above mentioned pitch. In this manner a perfectly rigid assembly of the supporting wall with its abutting surface and the multiple field is obtained, an assembly that can be effected according to factory methods without afteradjustment. According to the invention the supporting wall will then 55 often consist of the walls of a plurality of selector

compartments F placed on top of each other, said compartments being centered mutually in a lateral direction by means of lips and recesses E on the different compartments cooperating in the manner of tongue and groove, whereas centering in the direction of movement of the selector wipers is obtained by means of shoulders, not shown, which cooperate with the selector frame.

As should be clear from the above the invention renders possible the ready assembling of the multiple field and the various selector compartments in their correct mutual positions, so that said compartments will form together the equivalent of a solid selector frame, such compartments having the advantage, however, in comparison with a solid frame, of being capable of manufacturing in standardized units, so that they can be readily adapted to an exchange of any desired size.

In the embodiment of the invention shown on the drawing each selector compartment is intended to house two selector mechanisms. Each compartment has the shape of a box from which the bottom, the cover and the front wall has been removed, the end walls of said box being adapted to be secured on a selector frame by means of shoulders and screws, one angle iron ST only of said frame being shown on the drawing. On the drawing the left hand end wall has been cut away, as will be clear from the cross-hatched left hand portion of the supporting wall A. The compartment is provided with ledges Q₁ and Q₂ on which the base plates of the two selecting mechanisms are intended to rest. On the drawing only one selector has been shown in position in the compartment. The base plate, which is narrower than the compartment so that a clearance is formed at both of its side edges, is supported by the ledge Q₂. Movement of the base plate in a direction upwards is prevented by a projection UR on each side wall and by a spring FJ which cooperates with a piece AN and presses the plate downwards and inwards. As a consequence projections or lips L₁ and L₂ formed on the front edge of the selector, which projections pass through openings in the supporting wall, will bear on abutting surfaces D₁ and D₂ formed by the brackets K in the plane of the abutting surface of the plate A. A lip L₃, which cooperates with edges D₃ in an opening in the supporting wall, determines the position of the selecting mechanism in a lateral direction. A horizontal slot extending along the entire width of the multiple field allows insertion of the wipers BR₁ and BR₂ into the multiple field.

Along its side edges the base plate of the selector is slotted through a great portion of its depth as shown at O, so that the parts of the base plate resting on the ledge Q₂ will be mechanically connected with the plate only at the inner and outer edge of the plate. Through said arrangement transmission of vibrations from the selecting mechanism to the compartment is prevented.

As should be clear from the above the present invention entails the advantage that the position both of the selector multiple and of the selecting mechanism is positively determined with respect to a common abutting surface, rendering possible, as already mentioned, the assembling of the different parts of the selector according to factory methods. The only adjustment necessary after assembly of the selector consists in fixing the positions of the selector wipers BR₁,

BR₂ on the shaft which by means of toothed wheels KH transmits movement to the wipers during the selecting operation.

I claim:

1. In a selector arrangement, a number of selecting mechanisms having movable wipers, a bare wire multiple common to a plurality of said selecting mechanisms and extending substantially at right angle to the direction of movement of selector wipers during a selecting operation, a fixed wall plate arranged between said selecting mechanisms and the wire multiple and extending perpendicularly to the direction of movement of the wipers during the selecting operation, supporting members of insulating material each holding a bundle of multiple wires, shoulders on said supporting members for determining the position of said supporting member relative to the wall plate, and abutments on said wall plate for determining the position of the selecting mechanisms relative to the wall plate.

2. In a selector arrangement, a number of selecting mechanisms mounted on a base plate, a bare wire multiple common to a plurality of said selecting mechanisms and extending substantially at right angle to the direction of movement of selector wipers during a selecting operation, a fixed supporting wall plate arranged between said selecting mechanisms and the wire multiple and extending perpendicularly to the direction of movement of the wipers during the selecting operation, said wall plate having apertures therein, supporting members of insulating material each holding a bundle of multiple wires and provided with attachment noses adapted to engage said apertures, shoulders on the supporting members for determining the positions of said supporting members relative to the wall plate, and means on the wall plate for determining the position of the base plate of the selecting mechanisms relative to the wall plate.

3. In a selector arrangement, a number of selecting mechanisms mounted on a base plate, a bare wire multiple common to a plurality of said selecting mechanisms and extending substantially at right angle to the direction of movement of selector wipers during a selecting operation, a fixed supporting wall plate arranged between said selecting mechanisms and the wire multiple and extending perpendicularly to the direction of movement of the wipers during the selecting operation, said wall plate having apertures therein, supporting members of insulating material each holding a bundle of multiple wires and provided with attachment noses adapted to engage said apertures, shoulders on the supporting members for determining the positions of said supporting members relative to the wall plate, means on the wall plate for determining the position of the base plate of the selecting mechanisms relative to the wall plate, brackets carried by said wall plate, a ledge carried by said brackets, said ledge having recesses corresponding to projections on the supporting members of the wire bundles, and means for clamping the wire bundles in positions between the ledge and the wall plate.

4. A selector arrangement as claimed in claim 3, wherein portions of said brackets form abutments for projections on the base plates of the selector mechanisms.

5. A selector arrangement as claimed in claim 2 wherein the wall plate is provided with ledges for supporting the base plate of the selector mechanism.

6. In a selector arrangement, a number of selecting mechanisms having movable wipers, a bare wire multiple common to a plurality of said selecting mechanisms and extending substantially at right angle to the direction of movement of selector wipers during a selecting operation, a fixed wall plate arranged between said selecting mechanisms and the wire multiple and extending perpendicularly to the direction of

movement of the wipers during the selecting operation, supporting members of insulating material each holding a bundle of multiple wires, shoulders on said supporting members for determining the position of said supporting member relative to the wall plate, said wall plate having openings therein, and projections carried by said base plate extending into said openings.

HELGE EDVARD LINDSTRÖM.
